UNITED STATES PATENT OFFICE.

GILBERT Y. COURTNEY, OF HOLLAND, MICHIGAN.

TOOL-HOLDING MECHANISM.

1,083,193.

Specification of Letters Patent.

Patented Dec. 30, 1913.

Application filed February 15, 1913. Serial No. 748,665.

To all whom it may concern:

Be it known that I, GILBERT Y. COURTNEY, a citizen of the United States, residing at Holland, in the county of Ottawa and State of Michigan, have invented certain new and useful Improvements in Tool-Holding Mechanism, of which the following is a specification, reference being had therein to the accompanying drawings.

10 This invention relates to turrets or tool holders for lathes and has for its object the production of a tool holder whereby the different tools which are carried thereby may be successively brought into a proper operative position without having to reset each tool upon the turret or support.

Another object of this invention is the production of a simple and efficient means for loosening, unlocking, rotating, relocking, and tightening the rotary part of the turret so as to allow the tools to be swung to their proper operative positions, and holding them positively and rigidly in their correct position to act upon the metal or other material to be engaged or cut by the tools.

With these and other objects in view, this invention consists of certain novel constructions, combinations and arrangements of parts, as will be hereinafter fully described and claimed.

In the drawings:—Fig. 1 is a central vertical section through the turret or tool holder. Fig. 2 is a central vertical section taken at right angles to Fig. 1. Fig. 3 is a horizontal sectional view taken on line 3—3 of Fig. 2. Fig. 4 is a top plan view of the turret or tool holder. Fig. 5 is a side elevation of the upper end of the tool holder or turret. Fig. 6 is an enlarged sectional view through the spring locking plunger for holding the ratchet handle against rotation in one direction. Fig. 7 is a bottom plan view of the ratchet handle. Fig. 8 is a bottom plan view of the cam for operating the locking rod or bar. Fig. 9 is a detail perspective of one of the lugs which constitutes a guide for the locking rod or bar. Fig. 10 is a top plan view of the screw which engages the turret and to which the operating lever or handle is secured.

By referring to the drawings, it will be seen that 1, Fig. 1, designates the usual carriage of the lathe, to which carriage is secured the lower plate 2 of the turret by means of bolts and shoulder nuts 3 as indicated in

dotted lines in Fig. 3. The base 2 is provided with an aperture 4 in which aperture fits a locating stud 5 having a downwardly extending lug 6 which lug fits in the customary corresponding aperture in the carriage of the lathe 1. A supporting standard 7 is integrally secured centrally of the base 2 and is provided with a central left-handedly threaded bore 8 in which bore fits a screw 9 which screw is threaded left-handedly in that portion which fits in the bore 8, but is threaded right-handedly at its upper portion upon which the nut 19 fits. A supporting standard is also provided with an unthreaded portion 10 which unthreaded portion is provided with a key or feather 11 which fits in the key-way 12 formed in the side of the aperture 13 of the head 14 of the operating lever or handle 15.

The screw member 9 is provided with a centrally located aperture 16 which is normally closed by means of a threaded plug 17 and this aperture is provided with a right-angularly extending discharge aperture 18 for discharging the lubricant placed in the aperture 16 so as to efficiently lubricate the threads of the screw 9 as well as the under-side of the head 14 of the lever 15, the outer side of the standard 7, the inside and bottom of the cam wheel 22, and locking bar 24, and the portion of the turret casing 20 which rests upon the base 2. An adjusting nut 19 is screwed on the upper end of the screw 9 and clamps the handle or lever 15 in engagement with the upper end of the casing 20 of the turret. The lower end of the screw 9 is provided with a squared portion 21 which squared portion carries a loose collar 22 having an offset cam 23 formed upon one side thereof. The under-side of this offset portion is beveled as shown at 23 in Fig. 8, thus making the device a double cam for the purpose of raising the same over the locking bar 24 when the lever 15 is being returned to its normal position after rotating the turret casing 20.

A locking bar 24 is carried by the base plate 2 and slides under the cam wheel 22 and is provided with a shoulder portion 25 which shoulder portion 25 is adapted to be engaged by the cam portion 23 of the wheel 22 for reciprocating the bar 24 upon the base 2. The outer end of the bar 24 is widened as indicated at 26 so as to produce a firm gripping portion upon the outer end

to lock the outer casing 20 in engagement with the base 2. The outer edge of the bar 24 tapers as indicated at 27 so as to facilitate the entrance of the bar into one of the 5 notches 28 formed upon the outer face of the rotating casing 20.

The supporting standard 7 is provided with a pair of legs 29 which straddle the wheel 22 as illustrated in Fig. 3, and these 10 legs 29 are provided with apertures 30 through which the bar 24 passes. Slotted studs 31 are forced into the base 2 in the apertures 32 and in these slotted studs slides the bar 24 as illustrated in Fig. 3. A bowed 15 spring 33 has one end fixedly secured to one of the studs 31 by passing through the apertures 34 formed therein, whereas the other end of the spring 33 has its end bent downwardly and fitting in the aperture 35 formed 20 near the outer end of the bar 24 as illustrated in Fig. 3.

The outer casing 20 is so formed as to easily rotate upon the supporting member 7 and this supporting member 7 carries near 25 its upper end a spring pressed plunger 36 which plunger works in an aperture 37 formed in the upper end of the rotating casing 20. This plunger 36 is adapted to engage the ratchet teeth 38 formed upon the 30 under face of the head 14 of the operating lever or handle 15 so as to hold the same against rotation independently of the outer casing 20 in one direction. A plurality of threaded apertures 39 are formed in the 35 flange 40 of the rotating casing 20 and screws 41 are adapted to be threaded therethrough for firmly holding a tool in an operative position to perform the desired function when used upon the lathe. These tools 40 may be placed upon the casing 20 in the position as illustrated in Fig. 4 by dotted lines.

When it is desired to rotate the casing 20 and swing a new tool in position to operate, the handle 15 is pulled toward the operator 45 thereby causing the screw 9 to rotate unclamping the casing 20 from the base 2, swinging the wheel 22 and bringing the cam portion 23 in engagement with the shoulder 25 of the bar 24. This will slide the bar 24 50 to the position as indicated in dotted lines in Fig. 3 thereby releasing the same from the casing 20. In view of the fact that the plunger 36 will then engage the ratchet teeth 38 the casing 20 will also be rotated 55 for a quarter of a turn bringing the next succeeding tool to an operative position. As soon as the casing 20 has been rotated a quarter of a turn, the bar 24 will return to its normal position engaging the next succeeding notch 28 formed in the inner face 60 of the casing 20. The lever 15 can then be returned to its normal position by swinging the lever or handle to the right, clamping the casing 20 firmly to the base 2, the lever 65 or handle then being ready for operation

when it is desired to place the following tool in operation. Of course, it should be understood that the ratchet teeth 38 are so formed upon the under face of the handle 15 as to coöperate with the notches 28 of the 70 casing 20 and only cause the casing to rotate for a quarter of a turn. It will be seen that the spring 33 will cause the bar 24 to engage the notches 28; the cam member 23 of the wheel 22 having passed beyond the 75 shoulder 25.

From the foregoing description, it will be seen that the present tool holder or turret is especially adapted for use in connection with work where it is necessary to employ several 80 different tools and by having all the tools adjusted upon the same holder the different tools may be swung to operate immediately after the preceding tool has performed its function.

Having thus described the invention, what is claimed as new, is:—

1. A device of the class described comprising a base, a casing carried by said base, a supporting standard carried by said base, 90 said casing rotatably mounted upon said standard and adapted to turn thereon, a screw carried by said supporting standard, a reciprocating locking bar carried by said base, spring means engaging said bar for 95 normally holding the same in engagement with said casing, a cam member carried by said screw and engaging said locking bar for withdrawing the same from engagement with said casing whereby said casing 100 may be rotated when said screw is rotated, and said cam member being provided with a second cam portion upon its under side whereby said cam member will be raised over the locking bar when said screw is rotated to its normal position.

2. A device of the class described comprising a base, a casing, a supporting standard, means for locking said casing to said supporting standard, a central clamping 110 screw, an operating handle connected to said central clamping screw and provided with a plurality of ratchet teeth upon its under face, a rod carried within said supporting standard and engaging said operating handle whereby rotary movement will be imparted to said screw when said handle is rotated, and means engaging said operating handle for causing said casing to rotate when said operating handle is swung.

3. A device of the class described comprising a base, a supporting standard, a casing carried by said supporting standard and rotatably mounted thereon, a locking bar extending transversely of said supporting 125 standard, a vertically extending screw carried by said supporting standard and provided with a cam wheel upon its lower end, a shoulder formed upon said locking bar and adapted to be engaged by said cam 130

wheel for causing said locking bar to be withdrawn when said cam wheel is rotated, a ratchet operating handle carried by the upper end of said screw, a spring pressed 5 plunger engaging said ratchet handle and adapted to hold the same against independent rotation relative to said casing, means for holding tools in engagement with said casing, and means for normally holding said 10 sliding bar in engagement with said casing whereby said casing will be held against independent rotation relative to said supporting standard.

4. A device of the class described comprising a base, a supporting standard, a 15 casing, said casing provided with notches

formed upon its inner face, a locking bar slidably mounted upon said base and adapted to engage one of said notches formed in said casing, guiding studs carried by said base, said locking bar slidably mounted in said guiding studs, a spring secured to one of said studs, said spring engaging said sliding bar and adapted to normally hold the same in engagement with one of said 20 notches.

In testimony whereof I hereunto affix my signature in presence of two witnesses.

GILBERT Y. COURTNEY.
